UNITED STATES PATENT OFFICE.

VICTOR EMILIUSS HANSEN, OF BROOKLYN, NEW YORK, ASSIGNOR TO INTERNATIONAL CIGAR MACHINERY COMPANY, OF NEW YORK, N. Y., A CORPORATION OF NEW JERSEY.

CIGAR-WRAPPER CUTTER.

1,188,541.

Specification of Letters Patent. Patented June 27, 1916.

Application filed April 26, 1915. Serial No. 23,813.

To all whom it may concern:

Be it known that I, VICTOR EMILIUSS HANSEN, a citizen of the United States, residing at Brooklyn, county of Kings, and State of New York, have invented a new and useful Improvement in Cigar-Wrapper Cutters, of which the following is a specification.

This invention relates to an improvement in cigar wrapper cutters for cigar machines.

In cigar machines heretofore known, there has been employed a wrapper cutting bed inclosing a cutting die upon which a leaf from which a wrapper is to be cut is spread. These machines further employed one or 15 more rollers normally movable across the wrapper bed and die to effect the cutting of a wrapper from the leaf. In the operation of such machines there is danger of injury to the hands of an operator engaged in spreading a leaf upon the bed and die, unless 20 the hands are removed therefrom before the coöperating cutting roller is advanced. Heretofore, various mechanisms have been devised to prevent such injury by stopping 25 or slowing the machine as a whole, or the wrapper cutting mechanism, when the operator is tardy in removing the hands from the cutting bed and die after having spread a leaf thereupon. While such devices were 30 successfully operative, they were not entirely satisfactory because of their complicated character and liability to derangement or breakage. Moreover, stoppage of the machine in such cases resulted in a loss of production for the machine, which of course 35 increased the cost of the cigars made thereupon.

The main object of the present invention is the production of a cigar wrapper cutter 40 adapted for use on cigar machines in which the danger of injury to an operator's hands is eliminated without stoppage of the machine or any part thereof.

A further object is the production of a 45 device of this general character which is simpler, more durable and less expensive than those heretofore known.

With these and other objects not specifically mentioned in view, the invention 50 consists in certain constructions and combinations which will be hereinafter fully described and then specifically set forth in the claims hereunto appended.

In the accompanying drawings, which 55 form a part of this specification and in

which like characters of reference indicate the same or like parts, Figure 1 is a side elevation of a device constructed in accordance with the invention. Fig. 2 is a plan view of the device shown in Fig. 1. Fig. 3 is an end view, partly broken away, of the device shown in Figs. 1 and 2. Fig. 4 is a detail view, partly in section, of the coöperating cutting member and its mount, the section being taken on the line 4—4 in Fig. 2. Fig. 5 is a detail view, partly broken away, of the bracket supporting the coöperating cutting member; and of the mount for said member.

In carrying the invention into effect, there 70 is provided a wrapper bed and a cutting die within said bed, the two being shaped and arranged so that a leaf from which a wrapper is to be cut may be spread over the top thereof, and held thereon by suction or any 75 other suitable means well known in the art. There is further provided a coöperating cutting member normally movable across the wrapper bed and cutting die to effect the separation of a shaped wrapper from the 80 leaf. There is further provided means operative by an obstruction upon the wrapper bed and cutting die, such as an operator's hands, for causing the coöperating cutting member to be swung from its normal position and to pass the wrapper bed and cutting die without crossing the same, so that danger 85 of injury to the operator's hand is eliminated without stopping the machine or any 90 part thereof.

In the best constructions, there is provided a post and means for reciprocating the post a definite distance along one side of the wrapper bed and cutting die, and upon this post is pivotally mounted a bracket carrying the coöperating cutting member or members. In the best constructions also, the cutting members are pivotally and yieldably mounted in the bracket above referred to. In the best constructions also, a trip mechanism is employed for causing the coöperating cutting member to swing from its normal path to a path alongside the wrapper bed and cutting die.

All of the above elements may be varied in 105 construction within wide limits. The particular device selected to illustrate the invention is but one of many possible concrete embodiments of the same, and the invention therefore is not to be restricted to the precise 110

details of the structure shown and described. Moreover, certain parts of the invention are capable of use independent of other parts, and such independent use is contemplated.

5 In the device selected to illustrate the invention, 6 indicates the main bed of a cigar machine in connection with which the device is used, and 7 indicates a bracket secured to the bed 6 and adapted to support a wrapper bed 8 and cutting die 9, both of a type well known in the art. The operator spreads a leaf from which a shaped wrapper is to be cut over the wrapper bed 8 and cutting die 9, where the leaf is held by suction established 10 within the wrapper bed 8 and cutting die 9 by means not shown in the drawings, but which are well known in the art and which are omitted herefrom in the interest of brevity and clearness. Coöperating with the die 15 9 is a pair of cutting members or rollers 10. Each of these rollers 10 is mounted upon cone pivots 11 which are threaded or otherwise secured in a bracket 12. Each bracket 12 is pinned or otherwise secured to one end 20 of a short shaft 13. This shaft is journaled in a bracket 14. Upon the other end of each shaft 13 is pinned or otherwise secured an adjusting arm 15 and this arm is engaged by an adjusting screw 16 threaded in a 25 suitable projection extending from the bracket 14. Coiled around each shaft 13, at points intermediate its ends, is a torsion spring 17, one end of which is secured to the bracket 14 and the other end of which is secured to a collar 18 loosely mounted upon the shaft 13. Each of these collars is provided with a series of radial slots adapted to engage a pin 19 extending through the shaft 13. By means of the mechanism just 30 described, it will be understood that movement of the rollers 10 in a downward direction is limited by the arms 15 and adjusting screw 16; and that movement in an upward direction is in opposition to the force exerted by the torsion spring 17, so that the cutting members or rollers 10 are pivotally, 35 yieldably and adjustably mounted in the bracket 14.

The bracket 14 is pivotally mounted upon 40 a post 20. This post is given a reciprocating movement a definite distance alongside the wrapper bed 8 and cutting die 9 to cause the rollers 10 to roll over the edge of the die 9 and cut a wrapper from the leaf overlying the bed and die. To effect this movement, the post has attached thereto a rack 45 21 which is in mesh with and is operated by the gear wheel 22. The gear wheel 22 is fast upon one end of a short shaft 23, and upon 50 the other end of this short shaft is fixed a pinion 24. The pinion 24 is in mesh with a sector gear 25 formed on a cam lever 26, which lever is fast on a short shaft 27 journaled in bearings formed in a bracket 28 55 supported on the main frame 6. The cam le-

ver 26 carries a bowl 29 which tracks in a cam groove 30 formed in a cam 31, and this cam is fast upon a shaft 32 which is one of the main cam shafts of the cigar machine in connection with which the device is used.

70 For the purpose of guiding the post 20 in its reciprocatory movement, two studs 33 are provided which studs are held in place in the post by means of a set screw 34. The studs support rollers 35. The lower roller 75 35 tracks on a rail 36 secured to the bed 6 before referred to. The upper roller 35 tracks under a rail 37 which rail is supported at one end by a bracket 38, this being the bracket which supports the short shaft 23 80 before referred to. The other end of the rail 37 is supported by a bracket 39 rising from the bed 6 before referred to.

85 The mechanism thus far described provides the means whereby the rollers are normally reciprocated across the wrapper bed 8 and cutting die 9. For the purpose of causing the bracket 14 carrying the coöperating cutting rollers 10 on the post 20, in the event of an obstruction such as an operator's hand 90 being upon the wrapper bed and cutting die as the rollers advance, to swing from their normal position and pass without crossing the wrapper bed and cutting die, holding means are employed for holding the cutting 95 rollers 10 in their normal position, and a trip mechanism is employed for releasing the rollers from this position. In the device selected to illustrate the invention, this holding means and mechanism is as follows: 100 Coiled around the post 20 is a torsion spring 105 40, one end of which is secured to a collar 41 integral with the post 20, and the other end of which is secured to the bracket 14 at 42, as clearly shown in Fig. 3. This spring 110 105 is designed to normally rotate the bracket 14 carrying the cutting rollers 10 out of their path of normal movement. For the purpose of holding them in their normal position, there is provided a plunger 43 which 115 is slidable in the upper part of the bracket 14. This plunger 43 engages a recess or slot 44 formed in an enlarged head 45 carried by the post 20. This slot or recess extends around the periphery of the enlarged 120 head 45 for 90 degrees, and at each end thereof is sunk a depression marked 46. The plunger 43 normally engages one of these depressions, thus holding the bracket 125 holding means to keep the rollers 10 in their position shown in full lines in the figures; or in other words, in their normal operating position. Means are provided, however, for disengaging the plunger 43 from the depressions at one end of the recess or slot 44 130 125 so that the torsion spring 40 may swing the bracket about the post. This means includes a lever 47 which is fulcrumed at 48 to the bracket 14 before referred to. One end of this lever lies in front of the brackets 130

12 supporting the rollers 10. The other end engages the plunger 43 before referred to. Interposed between the bracket 14 and the lever 47 is a spring 49 which tends to hold the lever in the position shown in Figs. 1 and 2, which is the position in which it lies when the plunger 43 is operating as holding means to keep the rollers 10 in their normal operating position. As the cutting 10 rollers advance toward the die 9 in the direction of the arrow in Fig. 2, and in the event of an obstruction such as the operator's hand being upon the die at the time, the free end of the lever 47 will come in 15 contact with said obstruction and will be stopped thereby. In broken lines in Fig. 2, at the position marked B, the lever 47 is shown in the position it will occupy when it has met an obstruction. It will be readily 20 understood that in such event, the plunger 43 will be withdrawn from the depression 46 and that the torsion spring 40 will immediately cause the bracket 14 carrying the cutting rollers 10 to swing backwardly from 25 the position in which they are shown at B out of their normal path; and it will be seen by an inspection of Fig. 4, that there is a rise in the recess or slot 44 so that when the mechanism is tripped, the bracket 14 and 30 of course the cutting rollers carried thereby will not only be released so they will swing, but will be lifted by the plunger 43 moving around in the shallow part of the slot 44 so that an operator's fingers cannot be pinched 35 during this backward swinging movement of the bracket and rollers. The swinging movement is limited by the plunger 43 coming in contact and engaging the depression 46 at the other end of the slot. At C, in 40 Fig. 2, the parts are shown in broken lines in the position to which they swing; and it will be readily understood that they will be locked in that position by means of the plunger 43 engaging the second depression 45 46 in the head 45 until purposely released and brought back to normal position after the obstruction has been removed.

In view of the foregoing, a detailed description of the device is deemed unnecessary, and is omitted herefrom in the interest 50 of brevity.

What is claimed is:

1. In a cigar wrapper cutter, the combination with a wrapper bed, of a cutting die 55 mounted therein, a coöperating cutting member normally movable across said bed and die, and means operative by an obstruction on the bed and die to cause said member to swing clear of and pass without crossing the bed and die.

2. In a cigar wrapper cutter, the combination with a wrapper bed, of a cutting die mounted therein, a coöperating cutting member normally movable across said bed 60 and die, and an automatic trip mechanism

operative by an obstruction on the bed and die to cause said member to swing clear of and pass without crossing the bed and die.

3. In a cigar wrapper cutter, the combination with a wrapper bed, of a cutting die mounted therein, a coöperating cutting member normally movable across said bed and die, a reciprocating mount for the cutting member, and an automatic trip mechanism operative by an obstruction on the bed 75 and die to cause said member to swing upon its mount clear of and pass without crossing the bed and die.

4. In a cigar wrapper cutter, the combination with a wrapper bed, of a cutting die 80 mounted therein, a coöperating cutting member normally movable across said bed and die, a mount for the cutting member, means for reciprocating said mount a definite distance, and an automatic trip mechanism 85 operative by an obstruction on the bed and die to cause said member to swing upon its mount clear of and pass without crossing the bed and die.

5. In a cigar wrapper cutter, the combination with a wrapper bed, of a cutting die 90 mounted therein, a coöperating cutting member normally movable across said bed and die, a mount for the cutting member, cam controlled mechanism for reciprocating 95 said mount a definite distance, and an automatic trip mechanism operative by an obstruction on the bed and die to cause said member to swing upon its mount clear of and pass without crossing the bed and die. 100

6. In a cigar wrapper cutter, the combination with a wrapper bed, of a cutting die mounted therein, a coöperating cutting member normally movable across said bed and die, a traveling post upon which the 105 cutting member is pivotally supported, a rack secured to the post, a gear intermeshing with the rack, cam controlled means for operating the gear to give the post a definite reciprocatory movement, and an automatic 110 trip mechanism operative by an obstruction on the bed and die to cause said member to swing upon the post clear of and pass without crossing the bed and die.

7. In a cigar wrapper cutter, the combination with a wrapper bed, of a cutting die mounted therein, a coöperating cutting member normally movable across said bed and die, a traveling post upon which the cutting member is pivotally mounted, guides 115 120 for the post, a rack carried by the post, a gear intermeshing with the rack, cam controlled means for operating the gear to give the post a definite reciprocatory movement controlled by the guides, and an automatic 125 trip mechanism operative by an obstruction on the bed and die to cause said member to swing upon the post clear of and pass without crossing the bed and die.

8. In a cigar wrapper cutter, the combi- 130

- nation with a wrapper bed, of a cutting die mounted therein, a post, means for reciprocating the post a definite distance along one side of the wrapper bed, a bracket pivotally mounted upon the post, a pair of cutting members carried by the bracket and normally movable across said bed and die, and an automatic trip mechanism carried by the bracket and operative by an obstruction on the bed and die to cause the bracket and members to swing clear of and pass without crossing the bed and die.
9. In a cigar wrapper cutter, the combination with a wrapper bed, of a cutting die mounted therein, a post, means for reciprocating the post a definite distance along one side of the wrapper bed, a bracket pivotally mounted upon the post, a pair of cutting rollers carried by the bracket and normally movable across said bed and die, and an automatic trip mechanism carried by the bracket and operative by an obstruction on the bed and die to cause the bracket and rollers to swing clear of and pass without crossing the bed and die.
10. In a cigar wrapper cutter, the combination with a wrapper bed, of a cutting die mounted therein, a post, means for reciprocating the post a definite distance along one side of the wrapper bed, a bracket pivotally mounted upon the post, a pair of cutting members yieldably mounted in the bracket and normally movable across said bed and die, and an automatic trip mechanism carried by the bracket and operative by an obstruction on the bed and die to cause the bracket and members to swing clear of and pass without crossing the bed and die.
11. In a cigar wrapper cutter, the combination with a wrapper bed, of a cutting die mounted therein, a post having an enlarged fixed head, means for reciprocating the post a definite distance along one side of the wrapper bed, a bracket pivotally mounted upon the post below the head, a pair of cutting members carried by the bracket and normally movable across said bed and die, and an automatic trip mechanism carried by the bracket and operative by an obstruction on the bed and die to cause the bracket and members to swing clear of and pass without crossing the bed and die said trip mechanism including operative connections and a plunger engaging a suitable recess in the enlarged head of the post.
12. In a cigar wrapper cutter, the combination with a wrapper bed, of a cutting die mounted therein, a post having an enlarged fixed head, means for reciprocating the post a definite distance along one side of the wrapper bed, a bracket pivotally mounted upon the post below the head, a pair of cutting members carried by the bracket and normally movable across said bed and die, and an automatic trip mechanism carried by the bracket and operative by an obstruction on the bed and die to cause the bracket and members to swing clear of and pass without crossing the bed and die, said trip mechanism including operative connections and a plunger engaging a suitable recess in the head of the post and also including a torsion spring surrounding the post for producing a swinging movement of the bracket when the latter is released by the plunger.
13. In a cigar wrapper cutter, the combination with a wrapper bed, of a cutting die mounted therein, a post, means for reciprocating the post a definite distance along one side of the wrapper bed, a bracket pivotally mounted upon the post, a pair of cutting members carried by the bracket, means for normally holding said members in position to move across the cutting die, trip mechanism for releasing the holding means, and means acting when the holding means are so released for swinging the members to a position in which they pass without crossing the bed and die.
14. In a cigar wrapper cutter, the combination with a wrapper bed, of a cutting die mounted therein, a post, means for reciprocating the post a definite distance along one side of the wrapper bed, a bracket pivotally mounted upon the post, a pair of cutting rollers pivotally and yieldingly mounted in the bracket, means for normally holding said members in position to move across the cutting die, trip mechanism for releasing the holding means, and means acting when the holding means are so released for swinging the members to a position in which they pass without crossing the bed and die.
